UNITED STATES PATENT OFFICE.

AUGUSTUS W. WESSOLECK, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

FLEXIBLE TUBING.

1,140,425.

Specification of Letters Patent. Patented May 25, 1915.

Application filed January 31, 1914. Serial No. 815,680.

To all whom it may concern:

Be it known that I, AUGUSTUS W. WES-
SOLECK, a citizen of the United States, re-
siding at New Britain, county of Hartford,
5 State of Connecticut, have invented certain
new and useful Improvements in Flexible
Tubing, of which the following is a full,
clear, and exact description.

The present invention relates to flexible
10 shafting or tubing of the type used to in-
case, guide and protect flexible transmis-
sion shafting, such for instance as is used
in connection with speedometers and the
like.

15 The invention refers more particularly to
means for securely interlocking a sleeve
member to one end of such a flexible tubing
so that the two are rigidly interconnected.

20 The invention provides a specific means
of interconnection which may be availed of
at minimum expense and which will provide
an efficient form of interconnection.

25 To this end the invention comprises the
device described in detail in the following
specification taken in connection with the
accompanying drawings and illustrating a
preferable embodiment thereof.

30 In these drawings: Figure 1 is a view in
elevation of a flexible tubing end having a
sleeve coupled thereto in accordance with
the present invention. Fig. 2 is a view in
elevation of the sleeve member. Fig. 3 is a
35 view in elevation, partly in section, of one
form of flexible tubing which may be used
in connection with the present invention.
Figs. 4 and 5 are enlarged detail views illus-
trating the specific form of interlocking
means.

Referring to the drawings by numerals, 1
40 indicates a flexible inner tubing of the spiral
type which may be provided with a pro-
tecting "rustless" spiral tape 2 forming an
outer covering therefor. This is a well
known and standard construction of flexible
45 tubing well adapted to use in connection
with the present interlocking means, al-
though it will be understood that other
forms of flexible tubing may be employed.

50 3 designates a suitable sleeve member, a
portion of which incases one extremity of
the flexible tubing. This sleeve member
may assume various forms depending upon
the specific type of connection for its outer
end. In the case of speedometers, the outer

ends of the end sleeves of the flexible tubing 55
are usually constructed and arranged for
connection to the speedometer and pinion
casings respectively, but under the present
invention, the sleeve member is not limited
to any specific form. It is, however, pref- 60
erably constructed of metal which may be
indented.

With the end of the tubing inserted with-
in the sleeve member for a sufficient distance
to give the requisite overall length, the sleeve 65
member is placed beneath or between suit-
able punching dies which will give it a num-
ber of longitudinally extending indentations
4, and which will at the same time indent
both the facing strip 2, should it be em- 70
ployed, and the flexible tubing 1 so that the
tubing is provided with a recess and the
sleeve with an indented rib extending into
said recess and interlocking therewith. The
shape of the indentations will, of course, be 75
such as to provide locking abutment shoul-
ders or sides to the recessed portion of the
tubing, and the length of the indentations
will be such as to bridge at least two adja-
cent coils of the spiral tube. These series of 80
indentations 4 may extend about the sleeve
3 and may be of any desired number. It
will be evident that by thus deforming the
sleeve and providing it with a number of
indentations which will penetrate into and 85
indent these flexible tubing, and will extend
across and bridge adjacent spiral coils there-
of, the sleeve is firmly interlocked with the
tubing and is held against either rotary or
longitudinal movement relative thereto. 90

While I have herein described a prefer-
able embodiment of my invention, I desire
it understood that the same may be varied
in structure and in relative arrangement of
parts within the spirit of the invention and 95
the scope of the appended claims.

What I claim, therefore, and desire to se-
cure by Letters Patent is:

1. In a device of the character described,
a flexible spiral tubing, and a sleeve member 100
inclosing one end of said tubing, said sleeve
member and adjacent coils of said spiral tub-
ing having corresponding interengaging and
interlocking deformations, said deformations
extending longitudinally of the sleeve and
tubing and transversely of at least two ad-
jacent spiral coils. 105

2. In a device of the character described,

a spiral tubing, and a sleeve member inclosing one end of said tubing, said sleeve member having an indentation therein extending in a direction to bridge adjacent coils of said spiral tubing, said adjacent coils being provided with corresponding indentations interlocked with said sleeve indentation, said last named indentation interlocking said coils with each other and against relative 10 movement.

3. In a device of the character described, a spiral tubing, and a sleeve member inclosing one end of said tubing, said member and adjacent coils of said tubing being provided 15 with a series of spaced interlocking indentations, said indentations extending trans-

versely of adjacent coils of the tubing to interlock said coils with each other.

4. In a device of the character described, a spiral tubing, and a sleeve member inclos- 20 ing one end of said tubing, said member and adjacent coils of said tubing being provided with a series of spaced interlocking indentations, said indentations extending transversely of adjacent coils of the tubing to 25 interlock said coils with each other and to said sleeve, said series of indentations extending around said sleeve.

AUGUSTUS W. WESSOLECK.
